STOCKING

Barnett D. Gordon, Brookline, Mass.

Application August 12, 1949, Serial No. 4,441

Term of patent 14 years

(Cl. D47—7)

To all whom it may concern:

Be it known that I, Barnett D. Gordon, a citizen of the United States, residing at Brookline, in the county of Norfolk and State of Massachusetts, have invented a new, original, and ornamental Design for a Stocking, of which the following is a specification, reference being had to the accompanying drawings, forming part thereof.

The dominating feature of my invention resides in the particular border between the foot and heel reinforcement and the body of the stocking, in combination with the specific cap at the top of the heel splice.

I claim:

The ornamental design for a stocking, as shown and described.

BARNETT D. GORDON.
